UNITED STATES PATENT OFFICE.

DAVID L. MARTIN AND EDGAR L. FLOWERS, OF HICKORY, NORTH CAROLINA, ASSIGNEES OF ONE-FIFTH TO J. L. RIDDLE, ONE-FIFTH TO J. W. BLACKWELDER, AND ONE-FIFTH TO A. G. BOHANNON, ALL OF HICKORY, NORTH CAROLINA.

GAME-REGISTER.

1,073,262.

Specification of Letters Patent. Patented Sept. 16, 1913.

Application filed February 6, 1913. Serial No. 746,617.

To all whom it may concern:

Be it known that we, DAVID L. MARTIN and EDGAR L. FLOWERS, citizens of the United States, residing at Hickory, in the county of Catawba, State of North Carolina, have invented certain new and useful Improvements in Game-Registers; and we do hereby declare the following to be a full, clear, and exact description of the invention, such as will enable others skilled in the art to which it appertains to make and use the same.

This invention relates to improvements in game registers generally, although the invention is more particularly intended for use in connection with pool ball racks.

The principal object of the invention is to provide a register of the character described which will positively indicate the number of games played.

Another object of the invention is to provide a register for the purpose described in which a means of novel construction is employed for positively indicating the number of games lost by each of the different players.

A further object of the invention is to provide a game register of the character described which is comparatively simple in construction, is positive in operation, and is cheap to manufacture.

With these and other objects in view, the invention consists in the construction and novel combination of parts hereinafter fully described, illustrated in the accompanying drawings and pointed out in the claims here-to appended; it being understood that various changes in the form, proportion, size and minor details of construction within the scope of the claims may be resorted to without departing from the spirit or sacrificing any of the advantages of the invention.

In the drawings: Figure 1 is a front elevation of a game register constructed in accordance with our invention, Fig. 2 is a rear elevation of the casing, Fig. 3 is a vertical sectional view taken on the line 3-3 of Fig. 2, Fig. 4 is an enlarged detail horizontal sectional view taken on the line 4-4 of Fig. 1, Fig. 5 is an enlarged detail sectional view showing the gate in its normal or closing position, Fig. 6 is a similar view but showing the gate in its open position, Fig. 7 is an enlarged detail perspective view showing

the locking means employed for one of the gates and the actuating means therefor, Fig. 8 is a detail sectional view through the spring actuated brake, Fig. 9 is a plan view of one of the gates, Fig. 10 is a front elevation showing the modified form of our invention, Fig. 11 is an enlarged horizontal sectional view taken on the line 11-11 of Fig. 10, Fig. 12 is a cross sectional view taken on the line 12-12 of Fig. 11, and Fig. 13 is an enlarged detail perspective view showing the manner of mounting one of the gates.

Like reference numerals designate corresponding parts in all the figures of the drawings.

Referring to the drawings, A designates a pool ball rack which includes a back board 4 which is adapted to be secured to a wall or any other suitable support, and connected at one side of this board by means of hinges 5 is a forwardly swinging casing which is designated as a whole by the reference numeral 6. This casing includes a front wall 7, side walls 8-8 and top and bottom walls 9 and 10 respectively. A lock, 80 which is designated as a whole by the reference numeral 11 and which may be of any preferred construction, is associated with this casing.

Secured to the outer face of the front wall 7 and arranged on opposite sides of the center line thereof is a set of guide strips of serpentine formation, the strips 12 of one set being disposed opposite the strips 13 of the other set. The strips 12, which as above stated are spaced apart, form resultant runways 12^a and the strips 13 form resultant runways 13^a, said runways being respectively intended for use of the different players for the reception of pool balls. The lower ends of the strips 12 and 13 curve inwardly toward each other and the extreme ends thereof are spaced apart to form a resultant centrally disposed vertical discharge channel 14, said channel of course communicating with the runways 12^a and 13^a. The lower end portions of the outer strips 12 and 13 extend downwardly, as at 15-15, and are spaced apart to form a continuation of the channel 14, these strips extending to the bottom of the front wall 7. Slidably supported in suitable guides 16-16 which are carried by the bottom 10 of the

casing is a receptacle 17 of any suitable construction, the receptacle being disposed directly below the conduit 14 for receiving the pool balls as they are discharged therefrom. The opposed faces of adjacent strips 5 are grooved, and the upper ends thereof are enlarged, as at 18, to form a mouth or entrance for the balls.

Our invention further comprises a novel 10 means for locking the balls within the runways above the discharge channel 14. This mechanism consists of a plurality of horizontal openings 19 which are formed in the front walls 7 and respectively register with the various runways 12^a and 13^a. A gate 20 formed from a rectangular piece of flat metal is slidably mounted within each opening 19. The rear portion of each gate is formed with an opening 21 which is adapted 15 when the gate is drawn outwardly to register with the respective runway and permit the balls to pass therethrough. An inwardly extending T-shaped slot 22 communicates with the rear edge of each gate.

25 In order to lock the gate against movement, there is provided a supporting bar 23 which is disposed in parallel relation to the front wall 7, and is connected to the end walls 8—8 of the casing. This bar is disposed in the same plane as the openings 19, and extending forwardly from said bar in alignment with the openings is a plurality 30 of guides 24. The forward ends of these guides extend below the T-shaped slot 22 of the plates 20, and are each formed with a vertical bearing 25 which registers with a respective slot 22. Locking pins 26 are each mounted within a respective slot 22 and bearing 25 for vertical sliding movements.

35 Each pin is preferably formed of metal, and is of rectangular formation and is formed with a plurality of opposed notches 27—27 which are adapted when the pin is elevated to register with the T-shaped slot 22 of a respective gate 20, and thereby permit of 40 said gate being drawn forwardly. When, however, the pin is in its normal position, the notches 27 will be disposed below the gate, and as a result, said pin will have 45 interlocking engagement with the gate and thereby retain the same against movement. These gates are adapted to be withdrawn in 50 progression for a purpose which will be hereinafter more fully explained. It will thus be observed that in order to accomplish 55 this movement, it is necessary to progressively actuate the locking pins 26. Therefore, in order to accomplish this movement, a horizontally disposed shaft 28 is journaled in 60 suitable brackets 29—29 mounted on the rear face of the front wall 7, one end 28^a of said shaft being reduced and extending through one of the side walls 8 of the casing. This shaft is disposed above the locking 65 pins 26, and is connected to each pin by

means of a flexible connection 30, said connections being respectively connected to the shaft in progression at spaced points angularly around said shaft. Fixed on the reduced end 28^a of the shaft exterior of the 70 end wall 8 of the casing is a hand wheel 31 and formed in the periphery thereof is a plurality of recesses 32, there being one more recess than there are locking pins. These recesses are spaced equal distances apart. 75 Secured to the end wall 8 directly above the wheel 31 is a brake, which is designated as a whole by the reference numeral 33. This brake includes a vertically disposed cylinder 34 having an open lower end and a closed upper end 35, said upper end being centrally formed with an opening 36 where-through projects a stem 37 which carries a plunger 38 at its lower end, said plunger being normally urged to engage a respective 80 opening 32 of the wheel 31 by means of a coil spring 34^a which is disposed around said stem between the closed end 35 and the plunger 38. A finger-piece 39 is formed on the upper end of the stem and serves as a 85 means for retracting the plunger 38 when it is desired to release the wheel 31. When the shaft 28 has been once rotated all of said locking pins will have been lifted in progression, and this shaft will be prevented 90 from further rotation by means of a stop 40 which projects from the periphery of the wheel 31 and is adapted to engage the plunger 38. In order to automatically return the shaft 28 and consequently the locking 95 pins 26 to their normal lowered positions, a coil spring 41 is connected at one end, as at 42, to the front wall 7 and has its other end connected, as at 43, to one end of a flexible connection 44, the other end of said 100 connection being secured to the shaft 28. It will thus be observed that when said shaft is rotated in one direction, the coil springs 41 will be stretched. As the shaft is successively rotated to bring the respective 105 locking pins 26 into register with the respective gates, the shaft will be held against rotation by means of the plunger 38 engaging in a respective recess 32 of the wheel 31. Whenever it is desired to return the parts 110 to their normal positions, the plunger 38 is raised by means of the finger-piece 39 against the tension of the spring 34^a, and as a result, the coil spring 31 will cause the shaft 28 to return to its normal position. 115 Simultaneously with this movement the locking pins 26 will by their own weight slide down through the guide elements 24 and return to their normal positions.

Our invention further comprises a register, 120 which is of any preferred construction and is designated as a whole by the reference letter B. This register is attached to the front wall 7 of the casing and is preferably disposed between the respective sets of 125

strips 12 and 13. This register includes an actuating lever 45 which is normally held against movement by a coil spring 46. A plurality of cords 47 are each connected at 5 one end to the lever 45 and at its other end to an eye 48 mounted on the rear of a respective gate 20, said cords passing through suitable guides 49 carried by the supporting bar 23. It will thus be observed that when 10 any one of the gates 20 is pulled out the respective cord 47 will be actuated, and as a result, the lever 45 of the register B will be moved against the tension of the spring 46 and as a result actuate the register. 15 From the foregoing, it will be observed that in order to withdraw the balls from any or all of the runways, it is necessary to open the gates 20 successively and that as each of the said gates is opened or drawn out the 20 register B will be actuated. As a result of this construction, the register will indicate the number of persons who have been playing and by this means a check upon the cash returns can be accurately maintained. 25 By releasing the player's balls individually, clogging of the balls is prevented at the discharge into the passage 14.

Our invention further comprises a novel mechanism for registering the games lost by 30 different players. This mechanism includes a plurality of registers which are each designated as a whole by the reference letter C and may be of any preferred construction, there being as many of these registers as 35 there are runways. These registers are mounted upon the front wall 7 of the casing and are preferably disposed above the upper ends of the runways. Each register is actuated by means of a vertically disposed 40 push rod 50 which is slidably mounted within a groove 51 formed in the rear face of the front wall 7. Each rod has its lower end bent outwardly and thence downwardly, and has its extremity bent transversely of 45 the gate 20 to form a foot 53, said foot being disposed between the locking pin 26 and the front wall 7. An actuating element for each push rod 50 is carried by each gate 20 and is designated as a whole by the reference 50 numeral 54. Each element consists of a rock shaft 55 which is longitudinally disposed centrally of each gate 20 and is supported on its underface by means of bearings 56-56. The forward end of this shaft 55 is provided with a finger-piece 57, and the shaft is centrally formed with a semi-circular offset 58 which is adapted to normally lie around the opening 21 of said plate, and thereby permit of the balls to pass through 55 said opening. The inner end of each shaft 55 terminates in a rocker arm 59, said arm terminating in a rearwardly extending foot 60. When the gate 20 is drawn outward the proper player swings the shaft 55 by means 65 of the finger-piece 57, and as a result, the

foot 60 of the rocker arm 59 engages the foot 53 of the respective push rod 50 and raises said rod thereby actuating the register C.

In operation, let it be presumed that there 70 are six runways and six persons playing. Each player places the balls he makes within a respective runway. It will be observed that these runways are of serpentine formation, and as a result, downward descent of the balls will be greatly checked so that when they reach the gates 20 there will be but very little noise made. The gates 20 are, as above explained, normally disposed in the path of said runways and as a result, 75 prevent the balls from passing into the discharge channel 14. After all of the balls have been placed in the runways, a player can easily view said balls and thereby readily determine the number or amount which 80 he has made. The operator then rotates the wheel 31 until the notches 32 are brought successively into engagement with the spring actuated plunger 38 when the notches 27 of the locking pins 26 will be successively 85 brought into register with the slots 22 of the gates 20. The gates 20 may thus be 90 successively and progressively withdrawn so as to register the openings 20 thereof with the respective runways, and as a result, permit the balls to pass therethrough and thence into the receptacle 17 as will be readily understood. As each gate 20 is drawn out the register B is actuated as above described and by means of this register the 95 number of persons who have played will be indicated thereon. Thus, for instance, if this register has been in operation for several evenings and the register B indicates "65," this number will show that sixty-five 100 persons have played during those evenings, and as a result, the amount of money collected from them can be quickly ascertained, it being understood that each person pays a similar price for each game. The losing 105 players then actuate their respective register C, and as a result these registers will 110 respectively indicate the number of games lost by the different players.

At the completion of each game, each 115 player pulls out his slide 20, so that the register B will be actuated to register the fact that he has played. As a general rule the loser pays for the game, therefore, after each player has registered in the game, the 120 loser actuates his register C in addition to the register B.

In the modified form of our invention, as illustrated in Figs. 10 to 13 inclusive, the rack A is identical in construction with the 125 casing previously described. Attached to the front wall 7 is a plurality of pairs of spaced guide strips 61-61. These strips are disposed in spaced relation and are diagonally arranged across the wall 7 to form 130

downwardly inclined runways 62. Gates 63 each project through vertical slots formed in the front wall 7 adjacent the lower end of the respective runway. The runways 62 all 5 communicate at the lower end with a main discharge channel 64 which is serpentine in formation and is formed in one end wall of the casing. In this form the other parts of the invention are identical in construction as 10 above outlined, the only difference being in the manner of arranging them to meet the change in position of the runways.

What is claimed is:

1. In a game register, the combination 15 with a rack including a runway, of a gate slidably mounted transversely of the runway for controlling the passage of objects therealong, said gate having a T-shaped slot extending inwardly from the inner end thereof, a gravity locking pin slidably mounted in said slot and normally having interlocking engagement with said gate, said pin having opposed recesses formed in its lower portion, and means for raising the pin 20 to register the recesses thereof with the slot of the gate.

2. In a game register, the combination 25 with a rack including a runway, of a gate slidably mounted transversely of the runway for controlling the passage of objects therealong, said gate having a T-shaped slot extending inwardly from the inner end thereof, a guide element supported by the rack and disposed below the slot of the gate when 30 said gate is in its closed position, a gravity locking pin slidably mounted in the guide element and extending through the slot of the gate, said pin having opposed recesses formed in its lower portion, and means for 35 raising the pin to register the recesses thereof with the slot of the gate.

3. In a game register, the combination 40 with a rack including a runway, of a gate slidably mounted transversely of the runway for controlling the passage of objects therealong, said gate having a T-shaped slot extending inwardly from the inner end thereof, a gravity locking pin slidably mounted in 45 said slot and normally having interlocking engagement with said gate, said pin having opposed recesses formed in its lower portion, means for raising the pin to register the recesses thereof with the slot of the gate, and means for automatically returning the gate 50 to its closed position.

4. In a game register, the combination 55 with a rack including a runway, of a gate for controlling the passage of objects along the runway, a register, a gravity locking pin 60 normally having interlocking engagement with the gate, means for raising the pin out of said interlocking engagement with said gate, a connection between the gate and the register for actuating the latter upon opening the former, and means for automatically 65

returning said raising means to its initial position.

5. In a game register, the combination 70 with a rack including a runway, of a gate for controlling the passage of objects along the runway, a register, a gravity locking pin normally having interlocking engagement 75 with the gate, means for raising the pin out of said interlocking engagement with said gate, a rotary shaft disposed above the gate, and a flexible connection between the pin and shaft for raising said pin and disengaging the same from the gate upon rotation of said shaft.

6. In a game register, the combination 80 with a rack including a runway, of a gate for controlling the passage of objects along the runway, a register, a gravity locking pin normally having interlocking engagement 85 with the gate, means for raising the pin out of said interlocking engagement with said gate, a rotary shaft disposed above the gate, a flexible connection between the pin and shaft for raising said pin and disengaging the same from the gate upon rotation of said 90 shaft, and automatic means for returning the shaft to its normal position.

7. In a game register, the combination 95 with a rack including a runway, of a gate for controlling the passage of objects along the runway, a register, a gravity locking pin normally having interlocking engagement 100 with the gate, means for raising the pin out of said interlocking engagement with said gate, a rotary shaft disposed above the gate, a flexible connection between the pin and shaft for raising said pin and disengaging the same from the gate upon rotation of said shaft, and automatic means for returning the shaft to its normal position, said means consisting of a flexible connection having one 105 end fixed to the shaft and a coil spring having one end fixed to the rack and its other end connected to said connection.

8. In a game register, the combination 110 with a rack including a runway, of a gate for controlling the passage of objects along said runway, means including a gravity locking pin for locking the gate in its closed position, a rotary shaft disposed above the 115 gate, and a flexible connection between the pin and shaft for raising said pin and disengaging the same from the gate upon rotation of said shaft.

9. In a game register, the combination 120 with a rack including a runway, of a gate for controlling the passage of objects along said runway, means including a gravity locking pin for locking the gate in its closed position, a rotary shaft disposed above the 125 gate, a flexible connection between the pin and shaft for raising said pin and disengaging the same from the gate upon rotation of said shaft, and automatic means for returning the shaft to its normal position. 130

10. In a game register, the combination with a rack including a runway, of a gate for controlling the passage of objects along said runway, means including a gravity locking pin for locking the gate in its closed position, a rotary shaft disposed above the gate, a flexible connection between the pin and shaft for raising said pin and disengaging the same from the gate upon rotation of said shaft, means for locking the shaft against rotation when the pin is disengaged from the gate, and automatic means for returning the shaft to its normal position upon release of said shaft locking means. 5
15. 11. In a game register, the combination with a rack including a runway, of a gate for controlling the passage of objects along said runway, means including a gravity locking pin for locking the gate in its closed position, a rotary shaft disposed above the gate, a flexible connection between the pin and shaft for raising said pin and disengaging the same from the gate upon rotation of said shaft, a hand wheel fixed on said shaft, and a locking element engageable with the wheel for holding the shaft against rotation when the locking pin is disengaged from the gate. 20
25. 12. In a game register, the combination with a rack including a runway, of a gate for controlling the passage of objects along said runway, means including a gravity locking pin for locking the gate in its closed position, a rotary shaft disposed above the gate, a flexible connection between the pin and shaft for raising said pin and disengaging the same from the gate upon rotation of said shaft, a hand wheel fixed on said shaft and formed on its periphery with a recess, and a spring actuated plunger mounted on the rack and engageable in said recesses of the wheel for locking the shaft against rotation when the locking pin is disengaged from the gate. 30
35. 13. In a game register, the combination with a rack including a runway, of a gate for controlling the passage of objects along said runway, means including a gravity locking pin for locking the gate in its closed position, a rotary shaft disposed above the gate, a flexible connection between the pin and shaft for raising said pin and disengaging the same from the gate upon rotation of said shaft, a hand wheel fixed on said shaft and formed on its periphery with a recess, a spring actuated plunger mounted on the rack and engageable in said recesses of the wheel for locking the shaft against rotation when the locking pin is disengaged from the gate, and automatic means for returning the shaft to its normal position. 40
45. 14. In a game register, the combination with a rack including a runway, of a gate for controlling the passage of objects along said runway, a register, and means including
- an element carried by the gate for actuating the register when the gate is only in its open position. 50
55. 15. In a game register, the combination with a rack including a runway, of a gate for controlling the passage of objects along the runway, a register, a push rod operatively connected to the register, and means carried by the gate for actuating said rod when the gate is only in its open position. 70
60. 16. In a game register, the combination with a rack including a runway, of a gate for controlling the passage of objects along the runway, a register, a push rod operatively connected to the register, and means carried by the gate for actuating said rod when the gate is only in its open position, said means consisting of a rock shaft and a rocker arm extending from the shaft, the end of the arm being bent to form a foot adapted for engagement with the rod upon rotation of said shaft. 75
65. 17. In a game register, the combination with a rack including a runway, of a gate for controlling the passage of objects along the runway, means for locking the gate in its closed position, means for releasing said locking means, a register, and means including an element carried by the gate for actuating the register when the gate is only in its open position. 80
70. 18. In a game register, the combination with a rack including a runway, of a gate for controlling the passage of objects along the runway, means for locking the gate in its closed position, means for releasing said locking means, a register, a push rod operatively connected to the register, and means carried by the gate for actuating said rod when the gate is only in its open position. 85
75. 19. In a game register, the combination with a rack including a runway, of a gate for controlling the passage of objects along the runway, means for locking the gate in its closed position, means for releasing said locking means, a register, a push rod operatively connected to the register, and means carried by the gate for actuating said rod when the gate is only in its open position, said means consisting of a rock shaft and a rocker arm extending from the shaft, the end of the arm being bent to form a foot adapted for engagement with the rod upon rotation of said shaft. 90
80. 20. In a game register, the combination with a rack including a plurality of runways, of gates for respectively controlling the passage of objects through said runways, means for locking the gates in their closed positions, and means for progressively releasing said locking means. 95
85. 21. In a game register, the combination with a rack including a plurality of runways, of gates for respectively controlling the passage of objects through said runways, a register, and means including

ways, means for locking the gates in their closed positions, means including an actuating shaft for progressively releasing said locking means, and means for automatically 5 returning the shaft to its initial position.

22. In a game register, the combination with a rack including a plurality of runways, of gates for respectively controlling the passage of objects through said runways, a plurality of gravity locking pins for respectively locking the gates in their closed positions, a rotary shaft disposed above the gates, and a plurality of flexible connections between the pins and the shaft for progressively raising said pins and disengaging the same from the gates upon rotation of said shaft.

23. In a game register, the combination with a rack including a plurality of runways, of gates for respectively controlling the passage of objects through said runways, a plurality of gravity locking pins for respectively locking the gates in their closed positions, a rotary shaft disposed above the gates, a plurality of flexible connections between the pins and the shaft for progressively raising said pins and disengaging the same from the gates upon rotation of said shaft, and means for locking 30 said shaft against rotation when the pins are progressively disengaged from their respective gates.

24. In a game register, the combination with a rack including a plurality of runways, of gates for respectively controlling the passage of objects through said runways, a plurality of gravity locking pins for respectively locking the gates in their

closed positions, a rotary shaft disposed above the gates, a plurality of flexible connections between the pins and the shaft for progressively raising said pins and disengaging the same from the gates upon rotation of said shaft, a hand wheel fixed on said shaft, and a locking element engageable 45 with the wheel for holding the shaft against rotation when the locking pins are progressively arranged out of engagement with their respective gates.

25. In a game register, the combination with a rack including a plurality of runways, of gates for respectively controlling the passage of objects through said runways, a plurality of gravity locking pins for respectively locking the gates in their closed positions, a rotary shaft disposed above the gates, a plurality of flexible connections between the pins and the shaft for progressively raising said pins and disengaging the same from the gates upon rotation of said shaft, a hand wheel fixed on said shaft and formed on its periphery with a plurality of recesses, and a spring actuated plunger mounted on the rack and adapted to progressively engage in said recesses of the wheel when the pins are progressively disengaged from the gate upon rotation of said shaft.

In testimony whereof, we affix our signatures in presence of two witnesses.
